UNITED STATES PATENT OFFICE

150,480

DESIGN FOR A SPOON OR SIMILAR ARTICLE OF FLATWARE

Marion Weeber, New York, N. Y., assignor to National Silver Company, New York, N. Y., a corporation of New York

Application March 11, 1948, Serial No. 145,025

Term of patent 14 years

(Cl. D54—12)

To all whom it may concern:

Be it known that I, Marion Weeber, a citizen of the United States, residing in the city, county, and State of New York, have invented a new, original, and ornamental Design for a Spoon or Similar Article of Flatware, of which the following is a specification, reference being had to the accompanying drawing, forming a part thereof, in which:

Fig. 1 is a front elevational view of a spoon showing the essential features of my design in full lines, the back of the handle being plain.

Fig. 2 is a side elevation thereof.

I claim:
The ornamental design for a spoon or similar article of flatware, as shown and described.
MARION WEEBER.
